JOHN T. GODDARD, OF ROCHESTER, NEW YORK, ASSIGNOR OF ONE-HALF TO JOHN J. McINERNEY, OF ROCHESTER, NEW YORK.

BOMB.

1,372,744.

Specification of Letters Patent. Patented Mar. 29, 1921.

Application filed November 11, 1918, Serial No. 261,992. Renewed December 27, 1920. Serial No. 433,431.

To all whom it may concern:

Be it known that I, JOHN T. GODDARD, of Rochester, in the county of Monroe and State of New York, have invented certain new and useful Improvements in Bombs; and I do hereby declare the following to be a full, clear, and exact description of the same, reference being had to the accompanying drawings, forming a part of this specification, 10 and to the reference numerals marked thereon.

My present invention relates to explosives and more particularly to bombs of the kind required to be thrown by hand and fired by impact. The object of my invention is to provide a simple and efficient device of this character which can be thrown as a ball without possible danger of premature explosion. A further object of my invention 20 is to provide a bomb of this character which is absolutely safe against accidental discharge in the hands of the user, but which will explode with certainty upon impact. Another object of my invention is to provide a bomb which is safe and efficient and which can be made of any form most convenient for the user. More specifically, the 25 object of my invention is to provide a bomb comprising two spaced members, one of which contains an explosive and means for discharging the same, which means is normally locked but which is released when said members are moved relatively to each other by impact. To these and other ends 30 the invention resides in certain improvements and combinations of parts all as will be hereinafter more fully described, the novel features being pointed out in the claims at the end of the specification.

40 In the drawings:

Figure 1 is a plan view of my improved bomb with a portion of the outer shell sectioned away;

Fig. 2 is a view of the shell looking toward the safety devices;

Fig. 3 is a transverse central section showing the exploding devices in section;

Fig. 4 is a view similar to Fig. 3 with the inner shell moved relatively to the outer shell and the parts in the position in which the bomb is exploded;

Fig. 5 is a transverse central section of the inner shell showing the devices for exploding the bomb, taken on the line 5^x—5^x of Fig. 1;

Fig. 6 is a fragmentary view showing a detail of the devices for locking the exploding mechanism.

Similar reference numerals throughout the several views indicate the same parts. 60

A bomb constructed according to my invention comprises an outer shell 1 of sheet metal made of two sections each of which is pressed preferably in a hemispherical form and which are connected at their meeting edges to form a spherical shaped casing. I have shown my bomb of spherical form although it may be made of other forms if more suitable and convenient for the user. Within the outer shell 1 is a second shell 2 70 formed of heavier metal and constructed with an inner cavity 3 having an opening through its outer wall through which an explosive may be introduced into the cavity 3. The opening may be closed with a screw, 75 plug, or other suitable means 4. The walls of the inner member or shell are made with thickened portions so that when the explosive contained within the shell is fired, the shell will break into fragments along the 80 weakened portions. Diametrically through the inner shell is an opening or recess 5 adapted to receive a sleeve or hollow shaft 6 adapted to project at its ends from the shell. Adjacent the ends of the sleeve 85 6 the shell is sectioned away forming plane faces 7 substantially parallel with each other and transverse to the axis of the shaft 6. Near the middle of the shaft 6 it is provided with an enlarged portion 8 having 90 a driving fit within the recess in the shell and at its outer ends has reduced portions 9 forming bearings for the discharging or firing devices or triggers 10. Outside the bearing portions 9, the shaft is again reduced and receives bushings or washers 11 95 adapted to form thrust bearings for the triggers. In each of the faces 7 are seated priming devices 12 of any suitable character which communicate with the explosive within the shell and are adapted to receive primers which may be exploded by the action of the triggers. Seated in the recesses in the shell and surrounding the shaft 6 adjacent the central enlarged portion 8 are a 100 pair of springs 13 engaging at their outer ends the triggers 10 and anchored at their inner ends in a recess 14 formed in one side of the enlarged central portion of the shaft. Each of the triggers 10 is revolvably mount- 110

ed on the shaft 6 and has a bearing against the face 7 of the inner shell. Each of the triggers is of segmental form and is provided with a sharp or pointed portion 15 which cooperates with the primer to explode the same. Slidably mounted within the sleeve 6 are a pair of locking devices in the form of pins 17 having rounded heads 18 which normally engage depressions 19 in the wall of the outer shell, and support the inner shell within the outer shell. Each of the locking pins 17 has a projection 18^a adapted to engage a slot 19^a formed in the trigger adjacent its central opening. The sleeve 6 is also provided with a slot extending from its central opening through the bearing portion upon which the trigger is mounted and into the enlarged portion adjacent thereto.

20 The operation of the parts already described is as follows:

The inner shell receives a charge of explosive and the screw or plug 4 is placed in position. The locking pins 17 are then placed in position and the triggers moved to the position shown in Fig. 1 of the drawings, in which position they are locked by engaging with the lugs 18^a on the pins 17, which are held from rotation by engagement 30 with the slots in the sleeve 6. When in the position shown in Fig. 1, the springs 13 are under tension and tend to rotate the triggers 10 in the direction of the arrow shown in Fig. 1 to forcibly strike the pointed end of 35 the trigger against the primers. The locked position of the triggers is clearly shown in Fig. 3 and when the bomb is thrown the impact caused by striking tends to displace the inner shell relatively to the outer shell to 40 the position shown in Fig. 4. The camming action of the shoulders produced by the depressions 19 in the outer shell on the rounded heads of the locking pins, forces them inwardly moving the lugs 18^a out of engagement 45 with the triggers which are then moved into engagement with the primers by the force of the actuating springs 13. Means are provided for preventing premature actuation of the locking pins 17. For this 50 purpose, the inner shell is provided with a radial opening 19^b leading to a point adjacent the middle of the sleeve 6. The sleeve 6 is provided also with a recess communicating with the opening 19^b in the shell and 55 also with the central recess in the sleeve. Seated within this opening in the shell and slidably movable therein is a safety locking pin 21 which when moved inwardly to its full extent has its inner end projected between the inner ends of the locking pins 17 60 and positively prevents any actuation or movement of the locking pins such as would unlock the triggers. The pin 21 projects through an opening in the wall of the outer shell where it is provided with a shoulder

22 engaging its outer wall and terminating in an enlarged head 22^a and an expansion coil spring 23 engages the head and surrounds the shoulder 22 and is anchored against the outer wall of the outer shell. The spring 23 operates to automatically withdraw the pin 21 when the same is released from its retaining devices. Formed on the outer shell on opposite sides of the opening through which the pin 21 is inserted is a pair of ears 24 and 25. The ear 25 is provided with an opening which receives a pin 26 and a strap 27 of sheet metal or other suitable material has a bifurcated end 28 engaging the pin 26 and extends over 75 and engages the outer end of the pin 21 and then extends to a point in contact with the outer wall of the shell 1 where it is provided with an opening through which the ear 24 extends. A cotter pin 29 or other suitable means may extend through an opening in the ear 24 to secure the strap 27 in position on the shell. With the parts in the position shown in Fig. 3, the bomb is secure against accidental explosion and can be 80 safely handled and transported from place to place without danger of accidental explosion. In preparing the bomb for use it is only necessary to withdraw the cotter pin 29 when the expansion of the spring 23 85 throws out the safety pin 21 and the strap 27 swings on the pin 26 as a pivot until released from the shell, the slight friction between the spring pressed triggers 10 and the projections 18^a holds the locking pins 17 90 yieldably in their initial outward position and the shells in spaced relation while the bomb is passing through the air and until it strikes some object when discharge occurs as above described. In practice, it is intended that the user will place his finger on the strap 27 before removing the cotter pin and hold the safety strap in position 95 during the throwing operation.

It will be noted that I have produced a 100 bomb which is secure against accidental explosion, that can be thrown in any manner and is not liable to be exploded before impact. Also since the firing devices are positive in action, failure of operation of the 105 same is practically impossible.

I claim as my invention:

1. In a bomb, the combination with two spaced members movable relatively to each other, one of which is adapted to contain 110 an explosive, a rotatable firing device, means for rotating said firing device and thereby firing said explosive, means for locking the firing device against movement, and means controlled by the relative movement of said 115 spaced members for releasing said locking means and permitting said firing device to rotate and fire said explosive.

2. In a bomb, the combination with two spaced members movable relatively to each 120

other, one of which is adapted to contain an explosive, a firing device, means for actuating said firing device, a longitudinally slideable locking pin for retaining the firing device against actuation, and means actuated by said relative movement of the spaced members for sliding said pin to unlock the firing device.

3. In a bomb, the combination with two spaced members movable relatively to each other, one of which is adapted to contain an explosive, a firing device, means for actuating said firing device, a locking pin for retaining the firing device against actuation, means actuated by said relative movement of the spaced members for moving said pin to unlock the firing device, and releasable means for preventing premature actuation of said locking pin including a manually restrained device adapted to be released in the throwing operation.

4. In a bomb, the combination of inner and outer shells relatively displaceable by impact and one of which is adapted to contain an explosive, a rotatable discharging device, means for locking said discharging device against actuation, and means actuated by the relative displacement of said shells for releasing said locking means.

30 5. In a bomb, the combination of inner and outer shells relatively displaceable by impact and one of which is adapted to contain an explosive, a rotatable discharging device, resilient means for actuating said discharging device, means for locking said discharging means against actuation, and means actuated by the relative displacement of said shells for releasing said locking means.

40 6. In a bomb, the combination of inner and outer shells relatively displaceable by impact and one of which is adapted to contain an explosive, a rotatable discharging device, resilient means for actuating said discharging device, a movable pin engaging said discharging device to lock the same against actuation, and means for moving said pin to release the discharging device when said shells are relatively displaced.

50 7. In a bomb, the combination of an outer shell, an inner shell movable relatively thereto by impact and adapted to contain an explosive, a plurality of primer seats on said inner shell, spring actuated triggers co-operating with said primer seats, means for locking said triggers against actuation, and means for preventing a premature actuation of said locking means.

8. In a bomb, the combination of an outer shell, an inner shell movable relatively thereto by impact and adapted to contain an explosive, a plurality of primer seats on said inner shell, spring actuated triggers co-operating with said primer seats, means for locking said triggers against actuation, means

actuated by the relative movement of said shells for releasing said locking means, and means co-operating with said locking means for preventing a premature actuation thereof.

70 9. In a bomb, the combination of an outer shell, an inner shell movable relatively thereto and adapted to contain an explosive, firing devices, means adapted to be released by the movement of said inner shell relatively to the outer shell for locking said firing devices against actuation, and manually restrained means engaging said locking means and adapted to be released in the throwing operation for positively preventing premature actuation thereof.

75 10. In a bomb, the combination of an outer shell, an inner shell movable relatively thereto and adapted to contain an explosive, firing devices, means adapted to be released by the movement of said inner shell relatively to the outer shell for locking said firing devices against actuation, a pin engaging said locking means for positively preventing premature actuation thereof, and 80 means for automatically discharging said pin.

85 11. In a bomb, the combination of an outer shell, an inner shell movable relatively thereto and adapted to contain an explosive, firing devices, means adapted to be released by the movement of said inner shell relatively to the outer shell for locking said firing devices against actuation, a pin engaging said locking means for positively preventing premature actuation thereof, and 90 means for automatically discharging said pin.

95 12. In a bomb, the combination of an outer shell, an inner shell movable relatively thereto and adapted to contain an explosive, firing devices, means adapted to be released by the movement of said inner shell relatively to the outer shell for locking said firing devices against actuation, a pin engaging said locking means for positively preventing premature actuation thereof, a spring for moving said pin to automatically release said locking means.

105 13. In a bomb, the combination of an outer shell, an inner shell movable relatively thereto and adapted to contain an explosive, firing devices, means adapted to be released by the movement of said inner shell relatively to the outer shell for locking said firing devices against actuation, a pin engaging said locking means for positively preventing premature actuation thereof, means for automatically releasing said pin, and 115 means for retaining said pin against automatic actuation thereof.

120 14. In a bomb, the combination of an outer shell, an inner shell movable relatively thereto and adapted to contain an explosive, firing devices, means adapted to be released 130

by the movement of said inner shell relatively to the outer shell for locking said firing devices against actuation, a pin engaging said locking means for positively preventing premature actuation thereof, means for automatically releasing said pin, and releasable means secured to the outer shell adapted to engage said pin to secure it in engagement with said locking means.

10 15. In a bomb, the combination of an

outer shell, an inner shell adapted to contain an explosive, means within the inner shell actuated by impact for discharging the explosive, means movable in the outer shell for preventing the actuation of said discharging means, and means secured to said outer shell but removable therefrom during the throwing operation for preventing movement of said last named means.

JOHN T. GODDARD.
